RALPH L. KIMBALL, OF AUBURN, RHODE ISLAND.

DIRECTION INDICATOR.

Application filed August 25, 1926. Serial No. 131,424.

This invention relates to an improvement in direction indicators, more particularly adapted for use on motor vehicles, and has for its object to provide a direction indicator of this character adapted to be attached to the motor vehicle in a position to be viewed from the front thereof, with nesting sections mounted to be raised to expose the same to view, and each section provided with a different desired signal marking thereon.

A further object of this invention is to provide a plurality of nesting sections located in a suitable housing with means for raising the sections into position to expose the marking thereon, and with means for illuminating the marking.

A still further object of this invention is to provide a housing having nesting sections which may be raised to expose a signal marking thereon to be viewed from the front of the vehicle, and electric circuit closing means operated simultaneously with the exposing of the section for illuminating corresponding signals positioned to be viewed from the rear of the motor vehicle.

With these and other objects in view, the invention consists of certain novel features of construction, as will be more fully described, and particularly pointed out in the appended claims.

In the accompanying drawings:

Figure 1 is a fragmental side elevation showing the signal housing as mounted on the steering post of a motor vehicle in position to be viewed through the windshield thereof.

Figure 2 is a perspective view of the rear of the housing showing the cover raised.

Figure 3 is a perspective view of the front of the housing showing one of the sections raised to expose its signal thereon and the other sections nested therein.

Figure 4 is a perspective skeleton view showing one of the sections and its operating mechanism.

Figure 5 is a perspective view of a detail of the operating means for one of the sections.

Figure 6 is a perspective view of one of the springs for raising the section to expose the signal thereon.

Figure 7 is a perspective view of a spring for holding the latch means in locked position.

Figure 8 is a fragmental elevation with

the housing partly in section showing the position of the releasing means and the switches operated by the releasing means.

Figure 9 is a side elevation of one of the sections and its supporting arm, the same being shown in dotted lines in its raised position.

Figure 10 is a diagrammatic view showing the electric circuit which is used in conjunction with the signal device.

Figure 11 is an end elevation of the casing housing the rear signal device.

It is found, in the practical operation of direction indicators for automobiles, particularly those used in closed cars, of advantage to provide direction indicating means which may be readily operated by the driver of the vehicle to indicate to the approached traffic officer at the intersection of cross-roads the direction which it is desired that the vehicle should take.

It is also desirable to provide means operated in conjunction with a direction signal to be viewed from the front, a corresponding signal to be viewed from the rear of the vehicle in order that a following vehicle operator may be informed of any turn to the right or left which the vehicle is about to take; and to provide such a device, I have mounted nesting sections within a housing with means to selectively operate or raise the different sections to expose a signal marking thereon and indicate the direction the vehicle is about to take; and I have also provided electric means to be simultaneously operated to indicate at the rear of the vehicle a signal corresponding to that exposed in the front; and the following is a detailed description of the present embodiment of this invention and showing the one means by which these advantageous results may be accomplished.

With reference to the drawings, 10 designates the steering wheel of motor vehicle on the steering post 11, on which there is mounted a housing 12 by means of a bracket 13 clamped thereto. The housing 12 is in a position exposed to view the signal thereon through the windshield 14 of the vehicle, and comprises a box-like structure of any suitable shape with a cover 15 hinged to be raised by an upward swinging movement of one of the sections in the housing.

Suitably mounted on a rod 16 there are a plurality of sections 17, 18 and 19, each hav-

ing different direction marking thereon, and springs 20 and auxiliary springs 20' tending to swing the section from its housed position to raise the cover and expose to view the marking 21 on the section. Each of the sections comprises a sector-shaped end piece 22 and a face plate 23 which may be of any suitable transparent or translucent material and is provided with markings thereon, such as, "Turn" with an arrow in either direction as indicated in Figure 3, or the marking "Straight"; or any other desired markings may be used. These markings may be constructed by placing a mask or the like behind the transparent plate which is suitably illuminated by the lamps 24 and may be seen through the transparent or translucent covering. Each of the sections is operated in substantially the same manner, and therefore, but one of the sections as illustrated in Figure 4 will be described.

A tab 25 is carried by the face plate of each section, which is locked against the raising action of the spring 20 by means of pin 26 extending through opening 27 in the tab. The pin is held in locking position by means of a spring 28 acting through the links 29, 30 and rod 31. This locking pin is moved to release the section by a push rod 32 having a handle 33 extending outwardly through the housing, as illustrated in Figure 2. When the locking means is released by a downward pressure on the handle 33, a latch 34, which is more clearly shown in Figure 5, is swung by means of a spring 36 to position its offset portion 37 over the link 30 and retain the locking pin in its releasing position. The latch is moved to disengage the link 30 when the section returns to its housed or nested position by the edge 38 of the section engaging the V-shaped notched portion 39 of the offset end of the latch, to move it against the action of the spring and permit the releasing means to move upwardly by under-tension of a spring 28 and the pin 26 to engage the opening in the tab to hold the section in its housed position.

As will be seen in Figure 8, link 40 is pivoted to the sector-shaped end 22 of the section at 41 and to this link there is pivotally connected a second link 42 which is pivoted to a cross-rod 43 mounted in housing. When the section swings to its raised or exposed position as illustrated in dotted lines in Figure 9, these links through which spring 20 acts to raise the section serve to guide and assist in supporting the section in this position; and to retract or lower the exposed section, I have mounted a cross-rod 44 on links 45 which are also pivoted on the rod 43, and to this cross-rod a pull rod 46 is attached with a handle 47 through which the rod 44 may be moved to swing the link 42 and causes the section to swing downwardly to its housed and locked position.

The sector-shaped ends of each of the sections are suitably notched as at 48 to receive the retracting rod 44.

The raised section is illuminated by means of the electric lamps 24 which are located in an electric circuit, as illustrated in Figure 10, which is provided with a plurality of switches 49, any one of which when closed causes the lamps 24 to be lighted; the same illuminating means 24 is used for any of the sections raised. The switches 49 are closed by lever 50 pivoted at 51 which is beneath the link 30, and a movement of this link downwardly by means of a rod 32 and handle 33 causes the contacts of the switch 49 to be closed to complete the circuit and light the lamps 24. These contacts have sufficient inherent resiliency to spring apart upon the raising of the link 30 to the position in which the section is locked in its housing.

In order that a signal corresponding to that in front may be operated in the rear of the vehicle, lamp 52 is provided which has an indicating means 56 corresponding with the section operated by the handle 53; and lamp 54 is provided having an indicating means 57 which corresponds with the signal operated by the handle 55; and in order to illuminate corresponding signal simultaneously in the front and in the rear, a switch arm 58 is provided having inherent resiliency tending to move it toward one of the contact arms 49 which movement is permitted by the movement of the handle 53 to swing the lever 50 to close the contact arms of the said switch 49 and thus complete the desired circuit, as will be apparent in Figure 10, to illuminate the desired corresponding signals in the front and rear. The lamps 52 and 54 are mounted in any suitable casing such as that illustrated in Figure 11. The switches 58 are positioned to be operated only by the end releasing means to indicate in the rear a right or left turn, the middle releasing means being for the signal "Straight" which it is not necessary should be indicated in the rear.

From the foregoing it will be seen that I have provided a mechanically operated direction-indicating device for the front of a motor vehicle and provided electrically operated means for illuminating the front signal and at the same time illuminating the desired rear signal, the means for operating the signal being selective, and the entire unit being mounted in a suitable housing with binding posts 59 for attachment of suitable electric conductors, the selective operating means and the retracting means all being readily accessible to be easily and quickly manipulated by the driver of the motor vehicle.

The foregoing description is directed solely towards the construction illustrated, but I desire it to be understood that I re-

serve the privilege of resorting to all the mechanical changes to which the device is susceptible, the invention being defined and limited only by the terms of the appended 5 claims.

I claim:—

1. In a signal device, a plurality of nesting sections normally nested together, each carrying a different signal marking thereon, 10 manually selective mechanical means for automatically moving one of the sections to expose the desired signal, and mechanical means for returning the moved section to its place in the nested position.
- 15 2. In a signalling device, a housing, a cover therefor, a section carrying a signal marking thereon mounted in said housing, a spring tending to move said section and to raise the cover and expose the signal marking of the moved section to view, means for retaining the section in said housing against the action of the spring, and a handle for manually releasing said retaining means.

3. In a signal device, a housing, a cover

therefor, a plurality of sections nestingly 25 mounted in said housing, each carrying a different signal marking thereon, springs tending to move said sections and to raise the cover and expose the signal marking carried by said sections to view, separate 30 means for retaining each of said sections in said housing against the action of its spring, and selective means for releasing the retaining means of the desired section to permit movement thereof.

4. In a signalling device, a housing, a cover therefor, a section carrying a signal marking thereon mounted in said housing, a spring tending to move said section and to raise the cover and expose the signal marking on said moved section to view, means for retaining the section in said housing against the action of the spring, a handle for manually releasing said retaining means, and means for returning the moved section to 45 locked position in the housing.

In testimony whereof I affix my signature.

RALPH L. KIMBALL.
